COMBINED PHOTOFASH UNIT AND EXPOSURE CALCULATOR

Henry Dreyfuss, South Pasadena, Calif., assignor to Minneapolis-Honeywell Regulator Company, Minneapolis, Minn., a corporation of Delaware

Application August 24, 1956, Serial No. 42,720

Term of patent 7 years

(Cl. D61—1)

FIG. 1

FIG. 2

FIG. 3

Figure 1 is a rear elevational view of a combined photoflash unit and exposure calculator embodying my new design,

Figure 2 is a perspective view taken from a point beneath and in front of the article shown in Figure 1, and

Figure 3 is a perspective view taken from a point beneath and to the rear of the article shown in Figure 1.

The legible matter shown in broken lines is for illustrative purposes only.

I claim:

The ornamental design for a combined photoflash unit and exposure calculator, substantially as shown and described.
